UNITED STATES PATENT OFFICE.

ALEXANDER CZEZEPINSKI AND JOHN BARAN, OF BUFFALO, NEW YORK.

HYDRAULIC FAN.

1,171,322.

Specification of Letters Patent.

Patented Feb. 8, 1916.

Application filed March 20, 1915. Serial No. 15,734.

To all whom it may concern:

Be it known that we, (1) ALEXANDER CZEZEPINSKI and (2) JOHN BARAN, (1) a subject of the Czar of Russia and (2) a citizen of the United States of America, residing at Buffalo, in the county of Erie and State of New York, have invented certain new and useful Improvements in Hydraulic Fans, of which the following is a specification.

This invention relates to certain new and useful improvements in hydraulic fans.

An object of the invention is to provide a hydraulic fan in which a casing is so constructed as to house a water motor and to carry a projecting shaft extending through a removable front wall for supporting the fan on the projecting end thereof.

A further object of the invention is to provide a hydraulic fan which includes a specially formed casing suitably grooved and cut away to provide an inlet and outlet passage for water and to also afford a seat for the motor.

With the above general objects in view and others that will appear as the nature of the invention is better understood, the same consists in the novel construction, combination and arrangement of parts to be herein-after more fully described and then claimed.

In the accompanying drawing which shows the preferred embodiment of the present invention and to which reference is had herein by like characters designating corresponding parts throughout the several views:—Figure 1 is a vertical longitudinal sectional view. Fig. 2 is a vertical cross sectional view taken on line II—II of Fig. 1, and Fig. 3 is a horizontal sectional view taken on line III—III of Fig. 1.

Referring more in detail to the accompanying drawing, the reference numeral 10 designates the rear wall or main body portion of the water motor housing which is preferably of the shape shown in Fig. 1 to provide a reduced lower portion that may constitute a hand-hold and an enlarged continuously curved upper portion.

The main body portion 10 adjacent its upper end is provided with a circular recess or depression 11 while the neck portion of the member 10 is provided with a pair of fluid conducting passageways 12 and 13, the passageway 12 affording an inlet for

the propelling fluid, while the passageway 13 affords an outlet therefor, the lower ends of the passageways 12 and 13 being provided with outlet openings 14 and 15 respectively and having a closed front wall 16 as clearly indicated in Figs. 2 and 3. The central body portion 17 constituting the separating partition for the passageways 12 and 13 continues upwardly as at 17' to provide an extended inlet passageway 12' and terminates at 18 to provide an inlet opening 19 from the passageway 12' into the recess 11. An opening 20 affords communication between the recess 11 and the outlet passage 13, which passage 13 as before stated, communicated with the outlet opening 15. A water motor is mounted within the recess 11 and includes the central body portion 21 carrying radial blades 22 that wipe the side wall of the cylindrical recess 11, while a stub shaft 22 is carried by the body portion 21 and extends through the rear wall 10 of the device to constitute a suitable journal bearing. A removable front wall 24 is secured to the front wall of the body portion 10 as by suitable fastening members 25 and carries at its lower end an integral boss 26 provided with an opening 27 that registers with the inlet opening 14 and a second opening 28 that registers with the outlet opening 15, both of which openings in the boss 26 are internally screw-threaded to adapt the same for the reception of pipes or other fluid conducting members 29. An opening is provided adjacent the upper end and centrally of the front wall 24 through which extends the shaft 30 carried by the water motor 21 and mounted on said extended shaft 30 is a fan blower 31 detachably connected thereto as by a fastening screw 32. The inlet opening 12 is of cross sectional area reduced relative to the outlet passageway 13 so that the pressure in the inlet will be increased and therefore provide greater power for the water motor 21.

From the above description, it is believed that the operation of the device will be readily apparent, and while we have shown and described the preferred embodiment of the present invention, we do not wish to confine ourselves to the exact details of construction shown, as various forms, modifications and arrangements of the parts as

shown may be had without departing from the spirit and scope of the invention as claimed.

What we claim as new is:—

5 In a hydraulic motor, a body-portion, there being a cylindrical recess formed adjacent the upper end thereof, a water motor including stub axles journaled within the side walls of the body-portion and having a 10 solid hub received in said recess, radial vanes carried by the hub adapted to wipe the end wall of the recess, inlet and outlet passage-ways formed in the body-portion below the recess and communicating therewith, the inlet passageway extending to the 15 upper end of the body-portion and commu-

nicating with the recess at that point, there being inlet and outlet openings in the lower end of the body-portion communicating with the inlet and outlet passage-ways, and a removable front wall for the body-portion having openings therein communicating with the inlet and outlet openings of the body-portion. 20

In testimony whereof we affix our signatures in presence of two witnesses. 25

ALEXANDER CZEREPINSKI.
JOHN BARAN.
